US00D430055S

United States Patent [19]

Aiello et al.

[11] Patent Number: Des. 430,055

[45] Date of Patent: ** Aug. 29, 2000

[54] PASSIVE INFRARED OCCUPANCY SENSOR

[75] Inventors: **Justin Aiello**, Port Washington, N.Y.; **Wilfred Goldschmidt**, Weston; **Jeff Mullally**, Milford, both of Conn.; **R. Kurt Bender**, Dripping Springs, Tex.

[73] Assignee: **MYTECH**, Austin, Tex.

[**] Term: 14 Years

[21] Appl. No.: **29/115,166**

[22] Filed: **Dec. 8, 1999**

[51] LOC (7) Cl. **10-05**

[52] U.S. Cl. **D10/106**

[58] Field of Search D10/104, 106, D10/116, 121; 340/541, 543, 544, 545, 546, 547, 551, 571, 572, 573, 689
